UNITED STATES PATENT OFFICE.

MILTON ABRAMS, OF INDIANAPOLIS, INDIANA, ASSIGNOR OF ONE-HALF TO
FRED L. MCGAHAN, OF SAME PLACE.

FEED-WATER HEATER AND PURIFIER.

SPECIFICATION forming part of Letters Patent No. 423,653, dated March 18, 1890.

Application filed November 25, 1889. Serial No. 331,480. (No model.)

To all whom it may concern:

Be it known that I, MILTON ABRAMS, a citizen of the United States, residing at Indianapolis, in the county of Marion and State of Indiana, have invented a new and useful Improvement in Feed-Water Heaters and Purifiers, of which the following is a specification.

My invention relates to an improvement in that class of devices for heating and purifying the water supplied to steam-boilers in which the feed-water is subjected to the action of exhaust-steam from steam-engines.

The objects of my improvement are, first, to prevent the oil and grease carried over from the engine-cylinders by the exhaust steam from entering and commingling with the feed-water in the heater; and, second, to more thoroughly and completely separate the magnesia and lime compounds and other impurities from the feed-water, all as hereinafter fully explained.

The accompanying drawings illustrate my invention.

Figure 1 represents a central vertical section of my device. Fig. 2 represents a plan at the line *a*, Fig. 1. Fig. 3 represents a section on the line *b*, Fig. 2, and below the line *c*, Fig. 1.

A is a cylindrical tank having a closed top, and formed, preferably, of boiler-iron. In the lower part of tank *A* is a horizontal annular partition *B* and a circular partition *C*, which is riveted at the bottom to the tank and at the top to the inner edge of the annular partition *B*, thus forming a central well *D*. A portion of the annular space between the walls of the tank and the circular partition *C* is separated from the rest by vertical partitions *e* and *f*, which rise above the horizontal partition *B* and join at the top, thus forming, with the front plate *G*, an inclosed chamber *H*. The exhaust-steam from the engine enters chamber *H* through the inlet-pipe *I* and passes out through the bent pipe *J*, so that it is discharged directly downward into the central well *D*. For the purpose of discharging from the exhaust-steam the oil and grease brought over from the engine and held in mechanical suspension the arrangement of the inlet-pipe *I* and discharge-pipe *J* is such that

the steam entering through pipe *I* is projected against the front plate *G* or other similar obstruction, so that the greasy water contained therein is precipitated to the bottom of chamber *H*, while the steam passes out through pipe *J*.

K is a bent waste-pipe arranged in the bottom of chamber *H* for the discharge of the greasy water from the chamber.

The remainder of the annular space between the central well and the walls of the tank is divided by a series of vertical partitions *l* and *m* into a series of communicating compartments *n*, the first of which communicates through an opening *o* in the partition *C* with the central well *D*. The arrangement of these vertical partitions is such that there is a space over the top of the partitions *l*, as seen in dotted lines, Fig. 1, and a space under the partitions *m*, and they are arranged alternately so that water passes from the top of the first compartment *n* and from the bottom of the next compartment, and so on to the last compartment from which the feed-water is drawn through the pipe *p* for the supply of the boiler.

Q is an overflow-pipe arranged in the last of the compartments *n*. Each compartment is provided with a drain-pipe *r*, closed by a suitable valve, and a hand-hole *s*.

The upper part of the tank *A* is filled with a series of shallow pans *t* and *u*, pans *u* having a central opening *v*. The pans are arranged alternately, so that the supply of water entering through the supply-pipe *W* at the top of the tank overflows at the center of the first pan and at the edges of the next, and so on alternately until it falls onto the slightly-inclined annular partition *B* and drains into the central well *D*.

Y is the escape-pipe, through which the uncondensed steam escapes.

In operation water is pumped from the well or other source of supply through the supply-pipe *W* into the upper one of the series of pans, and from thence flows over the series of pans, as before explained, to the central well *D*. Exhaust-steam from the engine entering chamber *H* through pipe *I* is projected against the opposite wall of the chamber and

drops in the chamber the grease and oil and a portion of the water carried therein, and then passing through bent pipe J is projected downward into the central well D, thus heating 5 the water therein, and then passes upward, circulating around and between the pans t and u and heating the water contained in and overflowing from the pans. A large portion of the steam is condensed and flows 10 downward with the feed-water, and the remainder passes off through the escape-pipe Y. The heated water from the well D passes through the opening o to the first compartment n, and from thence over partitions l 15 and under partitions m successively until the last compartment is reached, from whence it is drawn out through the feed-water pipe p. Those elements in the water-supply which ordinarily form the harder portions of the scale 20 in the boiler are deposited on the pans t and u, while the lighter magnesia and lime compounds contained therein, which in other heaters and purifiers is partially separated by passing the water through hay or other filtering material, is deposited as a sediment in the 25 central well and the compartments n, in which the water stands comparatively still and under favorable conditions for the deposition of all the flocculent matter held in suspension 30 therein.

The separation of the grease held in suspension in the steam before it enters the feed-water effectually prevents it from passing into the boiler.

35 I claim as my invention—

1. In a feed-water heater, the combination 40 of a water-tank, an inclosed chamber formed within said tank and separated from the water-space thereof, a steam-supply pipe leading into said chamber from the outside, and a steam-discharge pipe leading from said

chamber to the water-space of the tank, all being arranged to co-operate substantially as specified, whereby the grease carried in suspension in the steam is precipitated before 45 entering the water-space, as set forth.

2. In a feed-water heater, the combination 50 of a water-tank, an inclosed chamber separated from the water-space thereof, a steam-supply pipe leading into said chamber from the outside, and a steam-discharge pipe leading from said chamber to the water-space of the tank, said steam supply and discharge pipes being arranged in different planes, whereby the steam on entering the chamber 55 is projected against one of its walls and its flow is obstructed or deflected, and foreign substances suspended in the steam are precipitated, substantially as set forth.

3. In a feed-water heater and purifier, the 60 combination, with the water-tank, of the central well formed in the lower part of the tank, a series of compartments arranged around said well, one of which compartments communicates with the well, and the compartments 65 communicating with each other in succession at the top of one and at the bottom of the other, the steam-supply pipe arranged to enter the tank above the central well, the water-supply pipe also arranged to enter the 70 tank above said well, and the water-discharge pipe leading from the last compartment, all arranged to co-operate substantially as specified, whereby the water in the well is heated by the steam and is withdrawn from the tank 75 through a series of settling-compartments, substantially as specified.

MILTON ABRAMS.
